MUTE FOR STRINGED MUSICAL INSTRUMENTS

Russell B. Kingman, Orange, N. J.

Application November 22, 1943, Serial No. 511,210

4 Claims. (Cl. 84—311)

This invention relates to an improved means for muting stringed musical instruments, such as violins, violas, cellos, bass-viols and the like.

The invention has for an object to provide a novel mute adapted to be attached to and carried by certain strings of the instrument subject to quick and easy manipulation, whereby it may be moved at will into and out of muting engagement with the string supporting bridge of the instrument, and so as to be thus readily available for use by the performer at any time during the playing of the instrument.

The invention has for another object to provide a novel mute which can be easily applied to and mounted behind the bridge on the instrument strings by which it is to be carried, so as to be slidable on said strings into and out of muting engagement with said bridge at will.

The invention has for a further object to furnish a mute of the kind mentioned which is provided with string engaging means so arranged that all tendency to buzzing, rattling or noisy vibration of the mute body per se, especially when the mute occupies its retracted inoperative position, is avoided.

Another object of the invention is to provide a mute of the kind mentioned which is substantially self-adjusting to variations in the spacing of the instrument strings by which it is to be carried.

Other objects of this invention, not at this time more particularly enumerated, will be understood from the following detailed description of the same.

Illustrative embodiments of this invention are shown in the accompanying drawings, in which:

Fig. 1 is a fragmentary plan view of a stringed instrument, showing the mute of this invention applied thereto, and wherein the mute is shown by full lines in its operative or in-service position, and by broken lines in its retracted or out-of-service position.

Fig. 2 is an enlarged side elevational view of the mute as mounted on instrument strings and as moved into muting engagement with the string supporting bridge of the instrument.

Fig. 3 is a forward end elevational view of the mute as carried by instrument strings, said view being drawn on a further enlarged scale; and Fig. 4 is a side elevational view thereof, the strings being omitted.

Fig. 5 is a plan view of a modified form of the mute device of this invention; Fig. 6 is a plan view in part section of another modified form

thereof; and Fig. 7 is a plan view in part section of still another modified form thereof.

Figs. 8, 9 and 10 are cross-sectional views of the mute body respectively showing various modifications of string receiving grooves or channels with which the sides thereof are provided.

Fig. 11 is a side elevational view of another modified form of the mute as mounted on instrument strings, and as moved to and held in retracted inoperative or out-of-service position.

Similar characters of reference are employed in the above described views, to indicate corresponding parts.

The reference character 11 indicates the body 15 of a stringed musical instrument, such e. g. as a violin, the strings 12 of which are anchored to a tail-piece 13, to pass thence over the bridge 14 to the neck of the instrument. The mute according to this invention is adapted to be mounted on a pair of the strings 12, in connection with the portions of the latter which extend between the tail-piece 13 and the bridge 14. Preferably the mute is mounted on a pair of intermediate strings 12, such e. g. as the D and A strings of a violin.

The mute, in one embodiment thereof as shown in Figs. 1 to 4 inclusive, comprises a block-like body 15 of suitable length, width and thickness, which may be made of ebony or like hard wood, plastic material, or other rigid material of desirable qualities. Formed as an integral part of said body 15, to project longitudinally forward from the front end thereof, is a thrust tongue 16 of less width than the distance between the strings 12 upon which the body 15 is mounted. Said thrust tongue 16 lies substantially in the plane of the top portion of said body 15, and said thrust tongue 16 is provided with an inwardly and downwardly shallowly inclined under surface or bottom face 17. Below said thrust tongue 16, the forward end of the body 15 provides a substantial area of contact surface 18 adapted, when the mute occupies a forwardly moved operative or in-service position, to abut and bear firmly against the rear face surface of the bridge 14. The lower portions 19 of the sides of said body 15 are inwardly inclined toward its bottom face, thus providing a bottom portion of cuneate formation in cross-section of less width at its tapered free end than the distance between the strings 12 with which the body is to be engaged. Formed in the upper portions of the sides of said body 15 are longitudinally extending, endwise open, string receiving channels or grooves 20.

Formed in connection with the upper face of the body 15, to upstand therefrom, is a suitably shaped finger-piece 21, whereby the body may be moved to and from operative bridge engaging position.

To apply the mute body 15 to the desired pair of instrument-strings 12 by which it is to be carried, said body 15 is aligned with and between the strings at a point behind the bridge 14, and with its cuneate bottom formation provided by the inwardly inclined sides 19 disposed to pass between said strings, as indicated by the relation of the mute to the dotted representation of the strings shown in Fig. 3. With the body 15 thus disposed, the same is merely pushed down between the strings 12, as indicated by the arrow in said Fig. 3, whereupon the cuneate lower portion of the body enters between the strings 12, so that the inclined sides 19 engage and easily spread apart the latter for downward movement of the mute body therebetween, until the string receiving channels or grooves 20 are brought into opposition to said strings, whereupon the latter snap into said channels or grooves 20, and thus slidably mount the mute body on said strings.

To position the mute in inoperative or out-of-service position, the body 15 is slid rearwardly on its supporting strings away from the bridge 14 and toward the tail-piece 13 of the instrument, and thus to the position indicated by the broken line representation of the mute body shown in Fig. 1.

To position the mute in operative or in-service position, wherein it engages the bridge 14 with muting effect, the body 15 is slid forward on its supporting strings up to the bridge 14, and thus to the position indicated by full line representation of the mute body shown in Figs. 1 and 2. As the mute body 15 approaches the bridge 14, its thrust tongue 16 will ride onto the top edge of the bridge, so as to engage the latter by its inclined under surface or bottom face 17. As this inclined under surface or bottom face 17 is advanced over the top edge of the bridge 14, it tends to exert an upward thrust upon the mute body 15 and upon the strings supporting the latter, so that by the time the contact surface 18 at the forward end of said body 15 firmly abuts the back of the bridge 14, the reactive stress of the up-thrust strings functions to frictionally bind the meeting surface portions of the thrust tongue and bridge edge together against relative displacement, thus firmly holding the mute body in contact with the bridge 14 with desired vibration dampening or muting effect.

To enhance the frictional grip of the body 15 upon the strings 12 by which it is supported, whereby to both secure the body against accidental longitudinal displacement, when occupying either in-service or out-of-service position, and at the same time so relate the body 15 to the supporting strings that any buzzing, rattling or noisy vibration of the body per se is eliminated, various means may be provided. For example, as shown in Figs. 2 to 4 inclusive, the string receiving channels or grooves 20 may be given a somewhat serpentine formation in vertical plane, thus providing spaced and staggered string snubbing points 22 along the length of said channels or grooves, which so engage the strings entered therein as to slightly angularly flex and snub the same to the body 15, whereby the body is held against vibratory movement relative to the carrying string portions, as well as against ac-

idental longitudinal shifting upon or along the latter. When this type of string receiving channel or groove is employed, the outlying portions of the snubbing points 22, contiguous to the open side of the channel or groove, are inwardly chamfered as at 23, whereby to provide lateral guide faces inclining inwardly to converge toward the medial longitudinal axis of the channel or groove 20 as a whole which serve to lead a string conformably into the latter, when the mute body is operatively inserted between the strings for engagement therewith.

Another arrangement for obtaining anti-rattling and anti-shift relation of the mute body 15 relative to its supporting strings 12, as shown in Fig. 5, comprises the provision of outwardly bulged portions 24 at the bottoms of the channels or grooves intermediate the ends thereof. These bulged portions tend to somewhat bow the channel or groove engaging portions of the strings 12, to thereby somewhat tensionally grip the mute body between the thus laterally stressed strings. Another somewhat similar arrangement is shown in Fig. 6, wherein an outwardly bowed leaf spring 25 is affixed in the bottom of each string receiving channel or groove of the mute body 15. The latter construction has the further advantage of rendering the body 15 substantially self-adjusting to variations in the spacing of the strings 12 by which it is to be carried.

In Fig. 7 there is shown another anti-buzzing or rattling and self-adjusting mute body construction in which the string receiving channels or grooves 20 are provided with yieldable spring 35 pressed string engaging shoes 26 disposed therein to extend along the interior thereof. These shoes 26 are respectively carried by shanks 27 extending into transverse slide way bores 28 formed in the mute body; said bores having diametrically enlarged inner end portions 29 providing shoulders engageable by annular flanges or stop portions 30 with which the inner ends of said shanks 27 are provided, whereby outward movement of the shoes 26 is limited. Spring means 31 is arranged between the oppositely extending shanks 27 so as to transmit yieldable outward thrust to the shoes. To facilitate production of the bores 28 and their end portions 29, as well as the assembly therewith of the shoe and shank 30 and spring structure, the mute body is split longitudinally into two halves 15' and 15'', which, after assembly of the structure is obtained, are suitably permanently joined together, as e. g. by gluing one to the other. It will be understood, that when the respective shoes 26 are engaged by the strings entered in the channels or groove 20, the same, by their yielding thrust, will not only adjust themselves to the spacing of the strings, but will so tensionally bear on the strings as to prevent buzzing, rattling or like undesirable vibration of the mute body.

A very simple form of anti-buzzing or rattling construction is shown in Fig. 8, wherein the string receiving channels or grooves 20, have their interior surfaces lined with a resilient lining means 32. This lining means may be made of any suitable comparatively soft and yieldable material. For example, a pile fabric, such as velour, velvet or the like may be used, and disposed with its pile face outward, the back of the same being cemented or adhered to the channel or groove surfaces. It will be obvious that such resilient lining means 32 will cushion the string and mute body against relative vibration, and at the same time will effect such frictional grip on the string as to prevent ac-

cidental longitudinal shifting displacement of the mute body, especially when the latter is retracted to inoperative or out-of-service position.

It will be understood that the string receiving channels or grooves 20 may be made of various cross-sectional shapes, such e. g. as of V-shape, as shown in Fig. 9, or of rigid V-shape as shown in Fig. 10, wherein an internal seat 20' is provided at the bottom interior thereof, in which the receiving string may seat itself, so as to be held against displacement.

In Fig. 11 is shown another modified construction of mute wherein the body 15 is provided with the bridge engaging thrust tongue 16 at its forward end, and with a similar rearwardly projecting thrust tongue 33 at its rearward end. Said rearward thrust tongue 33 is also provided with an inwardly and downwardly shallowly inclined under or bottom face 34. When the mute body 15 as thus constructed is retracted on the supporting strings 12 to out-of-service position, the rearward thrust tongue 33 will ride onto the top marginal surface of the tail-piece 13, as shown in Fig. 11, and, in so doing, tends to exert an upward thrust upon the mute body 15 and upon the supporting strings 12, so that reactive stress of the up-thrust strings functions to frictionally bind the rearward thrust tongue to the tail-piece, whereby to hold the body against forward movement along the strings, and thus against accidental displacement from out-of-service-position. At the same time, the up-thrust of the body 15 against the strings 12 also holds the former relative to the latter so as to eliminate buzzing, rattling or like undesirable vibration of the body when out of use. It will be obvious that the thrust tongue 33 may be optionally located so as to engage either the upper marginal surface or the lower marginal surface of the tail-piece 13, whereby, in either case thrust of the body against the strings will induce reactive stress in the latter for the purposes stated.

Having now described my invention, I claim:

1. A mute for a stringed instrument having a bridge by which its strings are supported comprising, a unitary block-like main body having endwise open longitudinal channels in opposite sides thereof to receive strings straddled thereby so as to slidably mount the body on said strings behind the bridge, said body having a cuneate bottom formation to facilitate its downward passage between said strings for application thereto, and a thrust tongue projecting longitudinally from the forward end of said body, said thrust tongue having an inwardly, downwardly and shallowly inclined underside adapted to ride onto the top edge of the bridge when said body is forwardly moved on said strings to abut the bridge with muting effect, whereby to produce sufficient down-thrusting tension in the engaged strings to frictionally retain said body against displacement from its muting relation to the bridge.

2. A mute for a stringed instrument having a bridge by which its strings are supported comprising, a unitary block-like main body having endwise open longitudinal channels in opposite

sides thereof to receive strings straddled thereby so as to slidably mount the body on said strings behind the bridge, a thrust tongue projecting longitudinally from the forward end of said body, said thrust tongue having an inwardly, downwardly and shallowly inclined underside adapted to ride onto the top edge of the bridge when said body is forwardly moved on said strings to abut the bridge with muting effect, whereby to produce sufficient down-thrusting tension in the engaged strings to frictionally retain said body against displacement from its muting relation to the bridge, and string engaging means in association with said channels for retaining the body and strings free from buzzing, rattling or relative vibration.

3. A mute for a stringed instrument having a bridge by which its strings are supported comprising, a unitary block-like main body having endwise open longitudinal channels in opposite sides thereof to receive strings straddled thereby so as to slidably mount the body on said strings behind the bridge, a thrust tongue projecting longitudinally from the forward end of said body, said thrust tongue having an inwardly, downwardly and shallowly inclined underside adapted to ride onto the top edge of the bridge when said body is forwardly moved on said strings to abut the bridge with muting effect, whereby to produce down-thrusting tension in the engaged strings to frictionally retain said body against displacement from its muting relation to the bridge, and string engaging means in association with said channels for retaining the body and strings free from buzzing, rattling or relative vibration, said latter means comprising a channel formation of shallow serpentine shape in vertical plane to provide spaced and staggered string snubbing points along the extent thereof.

4. A mute for a stringed instrument having a bridge by which its strings are supported comprising, a unitary block-like main body having endwise open longitudinal channels in opposite sides thereof to receive strings straddled thereby so as to slidably mount the body on said strings behind the bridge, said body having a cuneate bottom formation to facilitate its downward passage between said strings for application thereto, a thrust tongue projecting longitudinally from its forward end of said body, said thrust tongue having an inwardly, downwardly and shallowly inclined underside adapted to ride onto the top edge of the bridge when said body is forwardly moved on said strings to abut the bridge with muting effect, whereby to produce sufficient down-thrusting tension in the engaged strings to frictionally retain said body against displacement from its muting relation to the bridge, and string engaging means in association with said channels for retaining the body and strings free from buzzing, rattling or relative vibration, said latter means comprising a channel formation of shallow serpentine shape in vertical plane to provide spaced and staggered string snubbing points along the extent thereof.

RUSSELL B. KINGMAN.
